NOZZLE FOR SUCTION CLEANER

Edward O. Norris, Westport, Conn.

Application December 14, 1945, Serial No. 635,049

2 Claims. (Cl. 15—369)

1

This invention relates to nozzles for suction cleaners or the like, and more particularly to a nozzle for a suction scrubber which is adapted to dry the surface after the scrubbing operation.

An object of the invention is to provide a nozzle of the foregoing type having a novel and improved blade construction and mounting which enables the blade to conform to the contour of the surface to be cleaned.

Another object is to provide a nozzle which is suited to remove substantially all of the liquid from a surface.

Another object is to provide a self-sealing drip-proof nozzle for suction scrubbers of the above type.

Still another object is to provide a cleaning or scrubbing appliance of the above type having novel and improved details of construction and features of operation.

Various other objects and advantages will be apparent as the nature of the invention is more fully disclosed.

The suction nozzle disclosed herein for the purpose of illustrating the invention comprises a housing forming a chamber having an elongated suction opening. A floating resilient blade extends centrally through the nozzle chamber and projects through the opening therein to engage the surface to be scrubbed. The blade contains a number of transverse holes which convey fluid through the blade and also increase the transverse resiliency of the blade.

The sides of the resilient blade are provided with longitudinal shoulders shaped to seat on the housing to seal the opening and also to limit the outward movement of the blade, and resilient means such as springs engage the upper edge of the blade to hold the blade in its sealed position. The projecting portion of the blade is narrower than the opening through which it projects, hence it will shift freely from side to side in said opening to permit fluid to pass either face of the blade as the nozzle slides back and forth over the surface which is being cleaned. When the nozzle is raised off the floor, the blade will automatically seal the opening to prevent any liquid which may be trapped inside from dripping back onto the floor.

In the embodiment illustrated herein, the nozzle is mounted on wheels as a part of a scrubbing machine which is adapted to be moved over the floor in the manner of a vacuum cleaner. These wheels have shields containing orifices which open on the peripheral rims of the wheels and communicate with the chamber inside the

2

nozzle, so that, when said chamber is under suction during the drying phase of the scrubbing operation, the suction will dry the rims of the wheels and prevent unsightly streaking of the floor.

Although the novel features which are characteristic of this invention are set forth more in detail in the claims appended hereto, the nature and scope of the invention may be better understood by referring to the following description, taken in connection with the accompanying drawings forming a part thereof, in which a specific embodiment has been set forth for purposes of illustration.

15 In the drawings:

Fig. 1 is a side elevation of a suction cleaner having a nozzle embodying the present invention;

Fig. 2 is a broken front elevation of the nozzle;

Fig. 3 is a broken side elevation of the floating resilient blade member;

Fig. 4 is a transverse section taken on line 4—4 of Fig. 3;

Fig. 5 is a transverse sectional view of the nozzle, showing the same in operative position on the floor;

Fig. 6 is an end view of the nozzle;

Fig. 7 is a partial longitudinal sectional view thereof taken on the line 7—7 of Fig. 6; and

Fig. 8 is a transverse section, similar to Fig. 5, showing the position of the blade when the nozzle is lifted from the floor.

In the following description certain specific terms are used for convenience in referring to the various details of the invention. These terms, however, are to be interpreted as broadly as the state of the art will permit.

In the drawings, Fig. 1 shows a suction nozzle 1 having a flared body portion 2 embodied in a portable floor scrubbing machine of the type disclosed in application Serial No. 647,920, filed February 15, 1946.

The scrubbing machine proper, which forms no part of the present invention, includes a suction device 3 and a handle 4 containing a flexible conduit 5 which may be connected to a source of cleaning liquid such as soapy water, and a similar conduit 6 which may be connected to a drain.

The handle 4 of the machine carries a pivoted control lever 7 actuating a Bowden wire 8 which controls the operation of the suction device 3. For an understanding of the present invention, it is sufficient to say that in one position of the lever 7 cleaning liquid from conduit 5 is delivered to the flared body portion 2 of the nozzle, while

in another position of said lever, the suction device 3 creates an air suction which draws liquid upwardly through the nozzle for drying the surface and discharges the liquid through conduit 6 to a drain.

In the embodiment illustrated, the nozzle 1 comprises a rear wall 10 (Fig. 5) integral with the flared body portion 2, a front plate 12 secured to the wall 10 by screws 13, and end plates 14 (Fig. 7). The end plates 14 carry stub shafts 15 supporting wheels 16 by means of which the device may be wheeled across the floor or other surface to be cleaned and maintained in proper spaced relation therewith.

The nozzle 1 contains a chamber 17 and is formed at the bottom with longitudinal lips 11 having an elongated opening 18 therebetween for the passage of fluid between the chamber 17 and the surface to be cleaned. A passage 19 is formed in the rear side wall 10 for conveying fluid to and from said chamber 17. The edges of the lips 11 defining the opening 18 are preferably thin and sharp to prevent the accumulation of dust and dirt thereon and are shaped to form seats for the blade 20 to be described.

The chamber 17 contains a floating rectangular blade 20 of resilient material such as rubber, which extends centrally through said chamber. The blade 20 has a longitudinally spaced series of circular transverse holes 21 and is provided with slits 22 extending from said holes to the top of the blade to increase its transverse resiliency.

The resilient blade 20 is formed with longitudinal shoulders 23 on both sides thereof, which are shaped to engage the lips 11 to seal the opening 18 of the nozzle and also to limit the outward movement of the floating blade. Coil springs 24 are mounted in the chamber 17 between the top of said chamber and the top of the blade 20, contacting the portions of the top surface of the blade between the transverse slits 22. In the embodiment illustrated the springs 24 are positioned in holes 25 in the front plate 12 of the nozzle. The springs resiliently urged the blade 20 to its limiting position with the shoulders 23 seated on the lips 11 to seal the chamber 17. The upper part of the chamber 17 is of a size to receive and confine the blade, but to permit free sliding movement thereof in response to the pressure of the springs 24 and the pressure of the floor which forces the blade upwardly against the action of the springs.

The blade 20 projects outwardly through the opening 18 and has a lower resilient scraping surface 26 which is adapted to engage the surface to be cleaned. The blade 20 is slightly narrower than the opening 18 and thus provides a space for the passage of fluid on one side or the other of the blade as the blade slides back and forth over the surface which is being cleaned. In the embodiment illustrated, an insert 27 of abrasive material such as pressed copper wool, other metal wools, or the like, which has desirable cleaning properties extends along the entire length of the bottom 26 of the blade. Other cleaning substances, such as rubber impregnated with pumice, or a soft material, such as felt, may be used.

The nozzle may carry curved shields 28 having orifices which open on the peripheral rims of the wheels 16, and having ducts 30 which connect said orifices to the chamber 17 for removing fluid from the rims to said chamber upon the application of suction thereto.

In the operation of this device the blade 20 is retracted by contact with the floor to provide a fluid passage to the chamber 17 as indicated in Fig. 4. The hand lever 7 may be first actuated to supply liquid such as soapy water from the conduit 5 to the nozzle and thence through the chamber 17 and around the blade 20 to the floor, or the floor may be wet in other ways. The nozzle and blade are then pushed back and forth over the floor to scrub the same. The copper wool 27 assists in this scrubbing action.

At the end of the scrubbing operation, the hand lever 7 is actuated to start the suction device 3 and apply suction to the nozzle. The blade 20 scraping along the surface causes the water to pile up at its leading side around the opening between the blade and the lip 11 and the suction draws this water into the chamber 17 and through the opening 19 into the body 2 for discharge through the conduit 6 as more fully described in my copending application above mentioned.

When the nozzle is being moved to the left as viewed in Fig. 4, the blade is flexed to the right and the suction opening is on the side of the blade nearest the opening 19. Hence the liquid passes directly into the chamber 17 and through the opening 19. When the nozzle is moved to the right, the blade 20 is flexed to the left leaving the suction opening on the outside of the blade. The liquid then flows into the right side of the chamber 17, thence through the holes 21 in the blade to the opening 19.

It will be evident that when moved in either direction, the blade causes the liquid to pile up at the suction opening and to be removed by the suction of the device from the floor.

The holes 21 and slots 22 cause the blade to have sufficient flexibility to conform to an uneven floor surface so as to facilitate the scrubbing operation even when the surface is other than plane.

Any water which is carried around on the rims of the wheels 16 is removed by the ducts 30 so that the wheels remain substantially dry.

When the nozzle is lifted from the floor, the springs 24 cause the blade to seat on the lips 11 and seal the chamber 17 so as to prevent any water remaining in the chamber 17 from dripping back onto the floor.

It will be apparent from the above that the nozzle construction is suited to commercial use in floor scrubbers although it may also be applicable to vacuum cleaners operating without liquid provided the dimensions are made suitable for the purpose.

Although a specific embodiment has been shown and described for purposes of illustration, it will be evident to those skilled in the art that the invention is capable of various modifications and adaptations within the scope of the appended claims.

What is claimed is:

1. In a suction cleaner or the like, a nozzle comprising a casing having bottom and top walls forming a suction chamber and having an elongated suction opening in said bottom wall and an elongated groove in said top wall extending upwardly from said suction chamber and registering with said suction opening, a flexible blade having an upper portion mounted in said groove to slide vertically therein, said blade extending downwardly through said suction chamber with its lower end projecting downwardly through said suction opening to engage the surface to be

cleaned, said blade having longitudinal shoulders engageable with said bottom wall on opposite sides of said suction opening to seal said opening and to limit the outward movement of said blade, and spring means in said groove bearing against the top of said blade for resiliently urging said blade to its limiting sealed position, the projecting end of said blade being narrower than said suction opening and adapted to flex to leave a suction passage on one side or the other of said blade in response to the passage of the nozzle back and forth over a surface, said upper portion being restrained by said groove to cause the blade to return to central position in said suction opening due to its resilience.

2. A nozzle as set forth in claim 1 in which said blade divides said suction chamber into two parts extending respectively along opposite sides of said blade to communicate with the passages formed on both sides of said blade as it flexes, said casing being provided with a suction port communicating with one of said parts, and said blade being provided with a row of transverse holes to establish communication between said parts.
